VIBRATORY MOTOR

Joe White, Anderson, Ind., assignor to General
Motors Corporation, Detroit, Mich., a corpora-
tion of Delaware

Application October 3, 1934, Serial No. 746,668

6 Claims. (Cl. 172—126)

This invention relates to vibratory motors for horns or sound signals for power vehicles and more particularly to the type of vibratory motors used in sound signal which employs a diaphragm in which the vibrations of the diaphragm is effected by an armature connected therewith and operated by two electromagnets located on each side of the armature.

In certain aspects, the present invention constitutes an improvement over the apparatus described and claimed in the copending application of Robert M. Critchfield and Joe White, Serial No. 721,263, filed April 19, 1934. In that application there is disclosed a diaphragm horn which is positively actuated in each direction of its oscillations by electromagnets which operate alternately to attract an armature which is connected with the diaphragm. In order that one of the electromagnets of said application will operate upon the armature ahead of the other electromagnet so that the armature can be started oscillating, one of the electromagnet windings is connected directly with a source of current by a manually operated switch or horn button but the other electromagnet is connected through a relay switch having an electromagnetic winding in which the building up of current is delayed due to the reluctance of the magnetic circuit of the relay switch. The apparatus disclosed in said copending application is therefore dependent for its operation upon the fact that more time elapses between the closing of the manually operated switch and the complete energization of the horn motor electromagnet in circuit with the electromagnetic relay than between the closing of said switch and the complete energization of the horn motor electromagnet which is directly connected with the current source.

One of the objects of the present invention is to provide an improvement in the apparatus disclosed in the application above referred to by providing means whereby only one of the horn motor electromagnets is caused to operate upon the closing of the manually operated switch or horn button, the other of the horn motor electromagnets being prevented from being energized until the diaphragm has moved in one direction of its oscillatory movement. In other words the present invention provides that, when the horn button is closed only one of two horn diaphragm operating magnets will be effective to cause the diaphragm to move in one direction. This movement of the diaphragm in one direction causes the magnet which pulls it in that direction to become inoperative and to cause the other

electromagnet to be effective to pull the diaphragm in the opposite direction. Likewise, when the second mentioned electromagnet has moved the diaphragm in the opposite or second mentioned direction to a certain extent, then the second mentioned electromagnet will be rendered inoperative and the first mentioned electromagnet operative to move the diaphragm in the direction first mentioned. In this way the diaphragm is positively operated in both directions of its oscillatory movement, the control of the two operating magnets being effected directly in response to movements of the diaphragm or armature connected thereto.

Further objects and advantages of the present invention will be apparent from the following description, reference being had to the accompanying drawing, wherein a preferred embodiment of the present invention is clearly shown.

In the drawing:

Fig. 1 is a sectional view of a horn or sound signal embodying the present invention.

Fig. 2 is a wiring diagram showing the electrical circuits included in the present invention.

Referring to Fig. 1, 20 designates a frame having a circular flange 21 to which the peripheral edges of a diaphragm 22 and of a collar 23 are attached by bolts 24 and nuts 25. The collar 23 is provided with an internally threaded annular boss 26 which receives an externally threaded bushing 27 having an hexagonal head 27a and surrounding and attached to a horn projector or trumpet 28, the bell-shaped outlet of which is not shown. It will be noted that the diaphragm 22 is normally relatively close to the inside wall of the collar 23 and that the diaphragm is shaped so as to conform substantially to the contour of this inside wall. Therefore, as the diaphragm 22 is operated it operates to place the air between it and the collar 23 under a relatively high state of compression so that the air in the trumpet 28 will be set vigorously into a state of vibration.

The frame 20 adjustably supports a plurality of brackets, not shown. These brackets are riveted to opposite sides of laminated magnet frames or cores 35 and 38. The magnet frames 35 and 38 carry windings 40 and 41 respectively, as shown in Fig. 1.

The electromagnet 35, 40 and the electromagnet 38, 41 each cooperate with a common armature 42 mounted upon a rod 43 made from a hexagonal stock bar and having a reduced cylindrical portion 43a which passes through the diaphragm 22 and washers 44 and 45 and which

has a threaded portion cooperating with a nut 46 to clamp the diaphragm 22 between the washers 44 and 45 and certain parts between the nut 46 and the shoulder 47 of the rod 43. The rod 43 has a reduced cylindrical portion 43b which extends through the armature 42, a sleeve 48, washers 49 and 50 and a leaf spring member 51. The portion 43b is threaded to receive a nut 52, the tightening of which causes washer 50, spring 51, washer 49, sleeve 48 and diaphragm 42 to be clamped between said nut 52 and a shoulder 53 of the rod 43. In this way the rod 43 ties together the spring 51, the armature 42 and the diaphragm 22 in the desired spaced relation. By suitable adjusting means, not shown, the magnet frames 38 and 39 can be adjusted so as to obtain the desired air gaps between the magnet frames and the armature 42.

The frame 38 is provided with U-shaped brackets 63 and 64 which support opposite ends of the spring 51, said spring ends being fastened thereto by screws 72 and 63 which secure to said brackets respectively cross bars 64 and 65. Screws not shown secure to the bar 64 one end 25 of a pair of parallel bars 63, and the ends of a flexible plate 70. Screws, not shown, secure to the bar 65 the other ends of the bars 63, and the ends of a flexible plate 73. The flexible plates 70 and 73 insulatingly support two similar circuit breakers for respectively controlling the magnet windings 40 and 41.

The circuit breaker for controlling the winding 40 comprises a stationary contact 80 and a movable contact 81 attached respectively to a rigid bracket 82 and a flexible blade 83. An insulating strip 84 is located between the bracket 82 and the blade 83, and these parts are secured to the flexible plate 70 by rivets 85. As shown in Fig. 1 the bracket 82 and blade 83 are insulated from each other and the blade 83 is insulated from the plate 70. The insulating strip 84 extends slightly beyond the free end of the blade 83 so that it may be engaged by a washer 86 carried by the rod 43 and adjustably secured thereon by nuts 87 and 88 which are threaded on the extension 43b of the rod 43. The circuit breaker for controlling the magnet winding 41 comprises a stationary contact 90 and a movable contact 91 carried respectively by bracket 50 92 and a flexible blade 93. A non-conducting strip 94 is located between the bracket 92 and the blade 93 and extends a little beyond the end of the blade 93 to be engaged by the washer 86. The bracket 92, the strip 94 and the blade 93 55 are attached to the flexible plate 73 by rivets 95, the blade 93 being insulated from the bracket 92. The circuit breakers may be bodily adjusted, by any suitable adjusting means, relative to the washer 86 in order that the separation of the contact 81 from the contact 80 may be effected at the proper time during movement of the armature 42 toward the left as viewed in Fig. 1. Thus the relation of the strip 94 relative to the washer 86 may be adjusted in order that the 60 separation of contact 90 from contact 91 may take place in the proper instant during the travel of the armature 42 toward the right as viewed in Fig. 1. The screws not shown provide connections between the brackets 82 and 92 respectively with ground. This ground connection is caused through the frame of the horn which is mounted upon metallic parts of the vehicle to which the current source and horn button or manually operable switch 131, 132, 133 are 65 grounded, as shown in the diagram of Fig. 2.

Referring now to Fig. 2, the ground connections of brackets 82 and 92 are indicated at 182 and 192 respectively. The washer 86 is not shown in Fig. 2 but its equivalent is represented by the lugs 86a extending from the armature 42. A storage battery 120 grounded at 121 connected by a wire 122 with pivot 123 of an armature 124 is normally held by spring 125 against a stop 126. The armature 124 carries a contact 127 engageable with a stationary contact 128. Pivot 10 123 is connected with a relay winding 129 surrounding a core 130 in magnetic relation with the armature 124. Winding 129 is connected with a contact 131 of a horn button switch comprising a grounded stationary contact 132 and a movable contact 133 for bridging the contacts 131 and 132. A spring 134 normally maintains the contact 133 out of engagement with the contacts 131 and 132. The contact 133 is moved into switch closing position by pressing a non-conducting button 135 which carries the movable contact 133. Wire 136 connects the contact 128 with the magnet winding 40 which is connected by wire 137 with the blade 83 and with a resistance unit 138 which forms a parallel circuit with respect to the contacts 80 and 81 and with respect to the contacts 90 and 91. Magnet winding 41 is connected by wire 139 with the resistance 138 and with the blade 93 and is connected by a wire 140 with a relay contact 141 which cooperates with a movable contact 142 carried by an armature 143 pivoted at 144 and normally urged against a stop 145 by a spring 146. Wire 147 connects the armature 143 with wire 136. Armature 143 cooperates with an electromagnet 35 30 35 40 45 50 55 60 65 70 75 80 85 90 95 100 105 110 115 120 125 130 135 140 145 150 155 160 165 170 175 180 185 190 195 200 205 210 215 220 225 230 lay winding 149, hence the magnetic attraction between the magnet frame 35 and the armature 42 will be materially weakened. However, the armature 42 may continue to move slightly toward the frame 35 due to the momentum of said armature and the parts connected therewith. When, in response to the opening of the contacts 81 and 80, the relay 149 is energized sufficiently to cause the armature 143 to be attracted and to bring the contact 142 into engagement with the contact 141, the horn magnet winding 41 becomes directly connected with the battery through contacts 127 and 128 and contacts 142 and 141 and receives its full supply of current.

Then the armature 42 will be attracted toward the right toward the magnet frame 38 thereby causing the diaphragm 22 to move toward the right as viewed in Fig. 1. During movement of the armature 42 toward the right the contact 81 will reengage with the contact 80 and the contact 91 will be separated from the contact 90. This will cause a substantial reduction in the flow of current through the winding 41 and a substantial increase in the flow of current through the winding 40, whereupon the armature 42 and diaphragm 22 will swing toward the left. Hence the diaphragm will continue to oscillate so long as the button 135 is pressed to maintain the switch 131, 132, 133 closed.

The relay contacts 141, 142 remain closed so long as the switch 131, 132, 133 is held closed for the reason that the magnetic reluctance of the relay parts 143, 148 is so great that there is not sufficient time for the relay to become demagnetized between the time of the closing and the opening of contacts 81 and 80 while the diaphragm 22 is vibrating. To provide relatively high reluctance the core 148 is made of solid steel.

It is therefore apparent that the circuits are so arranged that, when the horn button or switch is closed, the armature can be attracted by only one of the horn magnets, the other one being non-operative until after the first magnet referred to has caused the armature to swing sufficiently to give the proper movement to the diaphragm. There is no likelihood that both magnets can be operative at the same time and the horn fail to sound as a consequence.

Obviously, the wire 122 might be directly connected with the wires 136 and 147 by a manually operable switch instead of the relay switch shown.

A relay switch is preferable since it is not always desirable to carry a relatively heavy current

through the relatively small manually operated switch which is usually mounted on the upper end of the steering column of the vehicle.

It is therefore apparent that the present invention provides means operable in response to the closing of the control switch for effecting the energization of only one magnet of the horn motor, in combination with circuit making and breaking devices which operate in response to movement of the armature of the horn motor to cause the two magnets thereafter to be alternately operative while the main switch is held closed.

While the embodiment of the present invention as herein disclosed, constitutes a preferred form, it is to be understood that other forms might be adopted, all coming within the scope of the claims which follow.

What is claimed is as follows:

1. An electrical system for a sounding signal, comprising in combination, a pair of opposed

electromagnets, a main operating switch for connecting a current source with the electromagnets, a pair of normally closed circuit breakers, means cooperating with the circuit breakers for causing the magnets to be energized alternately, and means cooperating therewith for withholding energizing current from one of the electromagnets until after the other of said electromagnets has become operative.

2. An electrical system for a sounding signal, comprising in combination, a pair of opposed electromagnets, an armature located between said electromagnets and arranged to be attracted in opposite directions thereby, a main controlling switch for connecting the magnets with a source of current, a pair of normally closed circuit breakers operated alternately by the movement of the armature for causing the magnets to be alternately affected to attract the armature, and means cooperating therewith for preventing the energization of one of the magnets until after the other of said magnets has been effective to attract the armature a certain distance.

3. An electrical system for a sounding signal, comprising in combination, a pair of opposed electromagnets, an armature located between said electromagnets and arranged to be attracted in opposite directions thereby, a main switch, circuit breakers operated alternately by the armature controlling circuits whereby the magnets are rendered alternately operative, and a normally open relay switch for controlling the circuit of one of the magnets and having a relay magnet winding normally inoperative and rendered operative by a certain movement of the armature produced by the operation of the other of the electromagnets.

4. An electrical system for a sounding signal, comprising in combination, a pair of opposed electromagnets, an armature located between the electromagnets and arranged to be attracted in opposite directions thereby, a main switch, a pair of independent circuit breakers normally closed and adapted to be operated alternately by the armature controlling circuits whereby the magnets are rendered alternately operative, and a resistance and a normally open relay switch operatively associated with one another for controlling the circuit of one of the magnets, said relay having a magnet winding normally inoperative and rendered operative by a certain movement of the armature produced by the operation of the other of the electromagnets.

5. An electrical system for a sounding signal, comprising in combination, a pair of opposed electromagnets, an armature located between the electromagnets and arranged to be attracted in opposite directions thereby, a main switch, a pair of independent circuit breakers normally closed and adapted to be operated alternately by the armature controlling circuits whereby the magnets are rendered alternately operative, and a resistance and an electro-responsive device operatively associated with one another, said electro-responsive device being inoperative upon closing of the main switch for controlling the circuit of one of the magnets and operative upon a certain movement of the armature produced by the operation of the other of the magnets.

6. An electrical system for a sounding signal, comprising in combination, a current source, a pair of opposed electromagnets, an armature located between the electromagnets and arranged to be attracted in opposite directions thereby, a

main switch, an electroresponsive device operatively associated with the main switch and adapted to connect the magnets with the current source, circuit breakers operated alternately by the armature controlling circuits whereby the magnets are rendered alternately operative, and a resistance and a normally open relay switch operatively associated with one another for controlling the circuit of one of the magnets, said

electroresponsive device being operative upon closing of the main switch to connect one of the magnets in a circuit to attract the armature and the relay switch being inoperative upon the closing of the main switch for controlling the circuit to the other magnet and operative when the first mentioned magnet has attracted the armature a certain distance. 5
